TRACTOR SEMITRAILER COMBINATION

William H. Wilson and Charles H. Land,
Detroit, Mich.

Application May 5, 1938, Serial No. 206,135

20 Claims. (Cl. 188—3)

This invention relates to a tractor semitrailer combination, and it has to do particularly with improvements by means of which service operations on the semitrailer are obtained. Such service operations may include operation of the trailer brakes. Certain phases of the invention are applicable to the so-called fully automatic semi-trailer wherein all operations may be effected from the driver's cab of the tractor, and certain phases of the invention may be arranged so that some of the operations may be controlled from the trailer for the so-called semi-automatic semitrailer.

In accordance with the invention the semitrailer is equipped with two types of brake operating means. One of such operating means takes care of brake operation while the vehicle is in transit or otherwise in use and connected to the tractor, and this operating means is preferably of the hydraulic type. The other brake operating means is arranged to take care of the brakes and hold them set when the trailer is parked or lodged separate from the tractor, and this brake operating means may be controlled from the tractor in the fully automatic type prior to tractor semitrailer disconnection. This brake operating means is preferably of a mechanical type for holding the brakes set over a long period of time, thus releasing the hydraulic system of brake holding stress or pressure. Preferably, the mechanical brake applying and holding means may be controlled from the trailer so that the brakes may be relieved at any time even though the trailer is parked.

The controlling mechanism which may be controlled from the cab of the tractor embodies essentially two groups of controlling means operable optionally from the cab of the tractor. The operator may adjust the controlling mechanism in what may be termed a normal condition so that while in transit the semitrailer brakes are operated hydraulically. When an uncoupling action is about to be accomplished, the operator may adjust the mechanism to bring the mechanical brake applying means into play. At this time mechanism is effective for operation from the cab of the tractor to release a device which maintains the draft coupling. The arrangement may be such that mechanism which is brought into play at the time an uncoupling action is desired operates both to apply the brakes and to release the draft coupling device. In a coupling operation, an arrangement is provided in the mechanical brake operating means for releasing the brake applying pressure, preferably at or near

the completion of the coupling action. Certain novel features of structure for obtaining these different actions are embodied in the structure for carrying out the invention. The above objects and other objects will be fully appreciated, as the following detailed description is followed in connection with the accompanying drawings. These drawings illustrate one form of mechanism for carrying out the invention.

Fig. 1 is a plan view of a semitrailer frame embodying the structure for carrying out the invention with some parts cut away to illustrate underlying structure.

Fig. 2 is a side elevational view of the forward portion of the semi-trailer and showing part of the tractor.

Fig. 3 is an enlarged plan view illustrating some of the mechanism embodied in the forward end of the semitrailer.

Fig. 4 is an enlarged detail view illustrating means for holding the mechanical brakes applied.

Fig. 5 is a side view of the mechanism illustrated in Fig. 4.

Fig. 6 is an enlarged view largely in cross section illustrating the king pin arrangement and some of the mechanism on the semitrailer and tractor.

Fig. 7 is an enlarged detail view largely in cross section illustrating control devices on the semitrailer.

Fig. 8 is a detail view illustrating some of the structure shown in Fig. 7.

Fig. 9 is a cross sectional view taken substantially on line 9—9 of Fig. 7.

Fig. 10 is a cross sectional view taken substantially on line 10—10 of Fig. 7.

Fig. 11 is a view showing some of the parts illustrated in Fig. 7 in a shifted position.

Fig. 12 is a cross sectional view illustrating the control mechanism on the upper and lower 5th wheels on the semitrailer and tractor respectively.

Fig. 13 is a view illustrating control mechanism mounted on the tractor for controlling optionally the actuation of certain operating means on the semi-trailer.

Fig. 14 is a view illustrating the movements through the king pin.

Fig. 15 is a sectional view taken substantially on line 15—15 of Fig. 14.

Fig. 16 is a detail view with parts in cross section illustrating the draft coupling.

Fig. 17 is a view illustrating the draft coupling and service bar member at about the time of the

completion of the uncoupling movement or the beginning of the coupling movement.

Fig. 18 is a view taken substantially on line 18-18 of Fig. 17 illustrating a detent function 5 for the draft latch and showing the coupled relationship of the parts.

In Fig. 1 the chassis of a semi-trailer is illustrated as comprising a frame 1 with wheels at the rear as illustrated at 2 and it is provided with 10 brakes generally illustrated at 3. The brake structure per se is not shown. The brakes are arranged to be actuated hydraulically, for which purpose a master hydraulic cylinder is shown at 4 with conduits 5 connecting the brakes. The 15 brakes are also arranged to be operated mechanically, for which purpose there is also illustrated rock-shaft 6 and a brake rod 7. It is within the invention to use the same brake structure 3 to be operated by both the hydraulic system and mechanical system, or separate brake structures 20 may be disposed in the brake housings 3.

Supporting legs 8 are pivotally connected to the frame for supporting the forward end when detached from the tractor, and one of the legs 25 is arranged to turn its pivot member 8a, upon which is mounted a projecting finger 9 (Fig. 5). A service bar 10 is mounted for reciprocation in the trailer frame, and it is connected to the legs as shown at 11. The forward end of the service 30 bar has an abutment or hook 12 arranged to slide in guideways 13. This structure and a draft coupling may be substantially in accordance with that shown in the William H. Wilson application Serial No. 178,853, filed December 9, 1937. The 35 tractor has a king pin 14, and pivotally mounted in the trailer frame is a draft hook 15 having a heel 16, Figs. 16 and 17. The forward end of the slot 13 is off-set, or in other words, has an angularly extending portion 17, as disclosed in 40 said Wilson application. The hook 12 pulls the service bar and therefore swings the supporting legs to supporting position as the tractor pulls away, and when the king pin passes through the off-set portion 17 of the guideway, there is a 45 lateral shift between the tractor and semitrailer fifth wheel members. Suitable means (not shown) may be provided to hold the legs in supporting position. When a coupling is made the tractor backs into the semitrailer and the 50 lateral arrangement causes the king pin to again move back of the hook 12 and the service bar is pushed rearwardly and the supporting legs elevated.

A lock member 20 locks the draft hook around 55 the king pin as shown in Fig. 16. For release purposes the locking member is retracted (Fig. 17) and held retracted by a spring pressed detent 21 (Fig. 18). As the tractor pulls away the king pin swings the draft hook from the Fig. 16 60 position to the Fig. 17 position. The draft hook is higher than the locking member 20 (Fig. 18) and it engages an inclined surface 22 on the detent and elevates it out of blocking position relative to the locking member 20, and the end of 65 the draft hook then blocks the locking member 20 as shown in Fig. 17. As the coupling is completed the portion 22 of the head which has the hook 12 engages the heel 16 and rocks the draft latch to king pin engaging position (Fig. 16), 70 and inasmuch as the detent 21 has been riding upon the surface of the latch, the locking member 20 moves into a position to hold the draft latch around the king pin (Fig. 16).

The above described construction relative to 75 the latch is one form of latch structure which

can be used with the present invention and has been described in order to disclose a fully operable mechanism. This latch structure, of course, is subject to variation.

Certain structure is mounted on the tractor, 5 particularly in the so-called fully automatic tractor semitrailer combination, and the tractor may have a rocking fifth wheel member 25 upon which a fifth wheel member 26 on the under side of the trailer frame rests when in coupled relationship 10 (Fig. 2). As aforementioned, the tractor carries the king pin 14 and this king pin is provided with two controlling pins 27 and 28 which are axially shiftable in the king pin. On the under side of the fifth wheel, there is mounted a rocker 15 shaft 29 (Fig. 13) upon which is splined or keyed a clutch member 30. Pivotally mounted upon the shaft 29 is an arm or yoke member 31 which has a pin and slot engagement 32 with the pin 27. Also pivotally mounted on the shaft 29 is 20 an arm or yoke 33 which has a pin and slot connection 34 with the control pin 28. A bell crank 35 is connected to the clutch member 30 and is normally arranged to be in clutching engagement with one of the arms 31 or 33. As 25 shown a coil spring 36 normally holds the clutch member 30 in engagement with arm 33. A control rod or cable 37 runs to the cab of the tractor so that the operator, by pulling on the member 37, may extend the spring 36 and shift the clutch 30 member 30 to the right (Fig. 13) to cause it to engage with the member 31. The clutch member 30 has a depending arm 40 connected to a rod 41 which in turn connects to a piston rod or diaphragm rod 42 in a cylinder or chamber 43 35 of a so-called booster. A suitable brake pedal in the tractor is arranged to apply the brakes and this causes movement of a piston or diaphragm in the booster 43 to pull on the rod 41 and rock the clutch member 30.

A rock-shaft 45 is pivotally mounted in the trailer and it has an arm 46 overlying the shifting pin 28 (Figs. 6 and 7). There is an arm on this rock-shaft connected by a rod 47 to operate the piston in the master cylinder 4 on the 45 trailer for applying the brakes hydraulically. 40

It will be observed that due to the spring 36 the clutch member 30 is normally positioned for actuation of the arm 33, pin 28 and shaft 45 to control the brakes of the semitrailer hydraulically. This is the so-called transit operation and at all times during operation of the combined vehicle the brakes may be applied hydraulically through these connections. Fig. 14 illustrates full and dotted lines showing the manner of the rocking of the arm 46 and shaft 45. 50

As shown in Figs. 3 and 7, another shaft 50 is mounted in axial alignment with the shaft 45, and this shaft is connected to a brake rod 51 acted upon by a spring 52. The shaft 50 is journaled in a sleeve 53, and clamped to the sleeve is a member with an arm 54 connected by a member 55 to a pivotally mounted arm or bell crank 56. The arm 56 has a bifurcated end which connects to a projecting stud 57 on the locking member 20. The sleeve 53 has an arm 58 which lies over the pin 27 (Figs. 3, 6 and 9). Therefore upward movement of the pin 27 will rock the sleeve and swing the arm 56 to retract the locking member 20 from the Fig. 16 position to the Fig. 17 position. 55

In this action there is an arrangement which forms a clutching engagement between the shafts 45 and 50. As illustrated in Fig. 7 the shaft 50 is slotted near its end and a pin 60 extends 75

through the slot and the pin is connected to a member 61 with a projecting finger 62. The pin 60 keys the member 61 to the shaft 59. Another member 63 which is rockable on a bearing 63' on shaft 50 (Fig. 7) has a sliding pin engagement 64 with the arm 58. The member 63 has a projecting pin 65 operating in a cam slot 66 of a fixed bracket member 67 which is attached to a transverse frame member 18. When the arm 58 is swung upwardly by movement of the pin 27 to retract the locking member 20, as above described, the member 63 is caused to rock with the sleeve 53 and arm 58 by reason of the sliding drive pin 64. The action of the pin 65 and cam slot 66, projects the members 63 and 61 so that the finger 62 is caused to project over or otherwise into interlocking engagement with the arm 46. Now, inasmuch as the locking member 20 is held in its retracted position by the detent 21, the position of the parts just described will remain in that position shown in Fig. 11.

The rod 51 is arranged to operate means for mechanically applying the brakes and for holding the brakes applied. The rod 51 has a pin and slot connection as at 70 with a swinging ratchet member 72 pivotally mounted as at 73, and the brake rod 7 is also connected to the ratchet pivotally as at 74. A pawl 75 acted upon by spring 76 engages the ratchet to hold it in position and this pawl is mounted upon a shaft 78 journaled in the frame and which is provided with a handle 79. There is a pawl release member 80 pivotally mounted upon the shaft 78 and acted upon by a torsion spring 81.

The normal position of the parts is illustrated in Figs. 4 and 5. When the rod 51 is pulled the ratchet is swung counter-clockwise to apply the brakes, and the brakes are held applied by the pawl and ratchet. The brakes may be relieved at any time while the trailer is parked by swinging the pawl by the means of the handle 79. When the supporting legs 8 are folded or held upwardly in transit position, the projection 9 may be in a position substantially as illustrated in the full lines in Fig. 5. The member 80 has a finger 82 overlying the heel of the pawl. When the legs move to supporting position, which movement is a clockwise swinging movement on the fulcrum 8a as Fig. 5 is viewed, the projection 9 moves past the swinging member 80, thus moving the member 80 against the action of the torsion spring, but this does not affect the pawl. This positions the projection 9 substantially in the dotted line position shown in Fig. 5. When the legs are swung upwardly into transit position, they swing counter-clockwise, and the projection 9 moves from the dotted line position to the full line position. In this action it engages the member 80, causes it to swing, and the finger 82 causes the pawl to swing out of engagement with the ratchet to thus release the brakes.

At this point the general operation might best be reiterated in more detail. Normally, the clutch member 30 on the tractor is in the position shown in Fig. 13 where it clutches with the member 33. Any time the operator wishes to apply the brakes he may depress the brake pedal (not shown) and this causes movement of the movable element in the booster 43. This action rocks the clutch member 30 and the member 33, and this shifts the pin 28 upwardly. The upward shift of the pin rocks the member 46 and shaft 45, and the brakes are applied hydraulically.

To uncouple the tractor and semitrailer, the operator in the cab of the tractor first pulls upon

the member 37, and this swings the clutch 30 into engagement with the arm 31. Now upon depression of the brake pedal the pin 28 is elevated by the arm 31, and this rocks the arm 58. This results in a rocking movement of the sleeve 53, by rod 55, and a retraction of the locking member 20 where it is held in retracted position by the detent 21. Also, this action causes the finger 62 to move into interlocking engagement with the arm 46 by reason of the cam 66 (Figs. 8 and 11). The position of the parts are thus maintained due to the locking member of the draft latch 22. The operator in the cab now releases the holding of the member 37 and the clutch member 30 shifts back to the Fig. 13 position. Now the operator again depresses the brake pedal (not shown), and this time the brakes may be applied hydraulically, as above described, because of the rocking of the shaft 45 through the means of the arm 46. At the same time the shaft 50 is rocked due to the interlocking arrangement of 46 and 62, and the brakes are applied mechanically by the rocking of the shaft 50 and the actuation of the rod 51, the swinging of the ratchet 72 and the applying of the brakes through the brake rods 7.

An important item now makes itself apparent. With the brakes thus applied and held applied by the pawl and ratchet the operator releases the brake pedal to allow the pin 28 to lower, and this takes the load of the brake application off of the hydraulic mechanism. Now the operator drives the tractor forwardly and uncouples, in which action the service bar pulls the supporting legs 8 into supporting position, and the semi-trailer is disconnected from the tractor. As long as the trailer remains parked in this manner the brakes are held mechanically and the hydraulic mechanism is released of brake-applying pressure. Therefore, any minor leakage of the fluid used in the hydraulic system may take place without affecting the application or the holding of the brakes in applied position. When the brakes are applied the spring 52 is compressed, and the spring normally holds the shaft 50 positioned in brake-released position. The spring normally positions the members 61 so that the finger 62 may be projected into proper cooperating relationship with the arm 46.

If at any time it is necessary to release the brakes while the trailer is parked, this may be done by swinging the handle 79 to release the pawl. The semitrailer may also be equipped with means for re-applying the brakes, which will be presently described. In making a connection between tractor and semitrailer, the tractor is backed into the trailer, and when the king pin is in its rearmost position, the draft latch swings, as above described, to locked position, thus releasing the locking member 20 so that it shifts to locking position as shown in Fig. 16. As the struts or legs 8 reach inoperative position, the projection 9 causes actuation of the pawl to release the mechanical operation of the brakes. This causes disengagement between the shafts 45 and 50 by reason of the rocking movement of the sleeve 53 and the retracting of the finger 62 from the Fig. 11 to the Fig. 9 position.

Now the member 20 is acted upon by means such as a spring so that it normally assumes locked position shown in Fig. 16. This spring may be associated with hand operated means for releasing the latch from a position on or near the trailer. The member 56, as illustrated, is in the form of a bell crank having a connection 80 75

with another bell crank 81 in turn connected to a rod 82 acted upon by a spring 83. This is the spring that normally holds the locking member 20 projected into locking position.

5 On the end of the rod 82 is a handle 84 which may be manipulated to release the locking member of the latch. If a full automatic control is not desired, then the handle 84 and associated parts may be used, or it may be desirable to employ this mechanism with the automatic mechanism.

The brakes may be applied by hand by the mechanical means, and for this purpose a rod 85 is attached to the shaft 50 for rocking the shaft.

15 The end of the rod 85 may extend to the forward end of the trailer frame where it has a one-way ball and socket connection 86 with a lever 87 pivoted as at 88. This lever may be arranged so that it may be extended in order to obtain an 20 adequate mechanical advantage, and to this end a handle portion 89 is pivotally mounted to the lever as at 90. This handle portion is arranged to be swung into alignment with the part 87 and be fastened thereto through the means of lug 91.

25 This, in effect, forms a folding handle which is folded up in use, as shown in Fig. 1. When the brakes have been released from the parked trailer they may again be applied by the manual swinging of the lever 87 to rock the shaft 50 and apply 30 the brakes in a manner as above described.

Thus it will be seen that the semitrailer brakes are normally hydraulically actuated during operation and may be applied and held applied by mechanical means operable either from the 35 tractor cab or from the side of the trailer frame when it is desired to uncouple the tractor and semi-trailer. Also the brakes may be released and reapplied during the parking of the semitrailer. Notwithstanding the fact that the trailer brakes are hydraulically actuated in transit, and notwithstanding the fact that they may be applied from the cab of the tractor for release purposes, the hydraulic mechanism is relieved from 40 brake applying pressure while the trailer is parked.

45 We claim:

1. In a tractor semitrailer combination, brakes for the wheels of the semitrailer, hydraulic means on the trailer for operating the brakes, means 50 on the tractor operable to apply the trailer brakes through the said hydraulic means, mechanical means on the trailer for operating and applying the brakes, means in the mechanical means for holding the brakes applied upon tractor semitrailer separation, means on the trailer for releasing the holding means for release of the brakes, and means on the trailer for reapplying the brakes by said mechanical means.

2. In a tractor semitrailer combination, brakes 60 for the wheels of the semitrailer, hydraulic means on the trailer for applying the brakes, mechanical means on the trailer for operating and applying the brakes, means on the tractor for exerting brake-applying pressure, means operable at 65 will for selectively delivering the brake-applying pressure to the hydraulic means alone and to the mechanical means, and means in the mechanical means for holding the brakes applied for tractor semi-trailer separation to thereby relieve the hydraulic means on the work of holding the brakes applied.

3. In a tractor semitrailer combination, brakes 70 for the wheels of the semitrailer, hydraulic and mechanical brake-applying means on the semitrailer, means on the tractor operable to deliver

brake-applying forces to the hydraulic means, means operable at will to direct the brake-applying forces on the tractor to the mechanical means to apply the brakes by the mechanical means, and means in the mechanical means for holding 5 the brakes applied upon tractor semitrailer separation to relieve the hydraulic means of brake-applying forces.

4. In a tractor semitrailer combination, brakes for the wheels of the semitrailer, hydraulic brake- 10 applying means on the semitrailer, mechanical brake-applying means on the semitrailer, a draft coupling between the tractor and semitrailer, including a king pin, two axially shiftable pins in the king pin for operating the hydraulic and me- 15 chanical brake-applying means, and means on the tractor for selectively shifting one of said pins.

5. In a tractor semitrailer combination, brakes for the wheels of the semitrailer, hydraulic means 20 on the semitrailer for applying the brakes, a draft coupling including a king pin, an axially shift- 25 able pin in the king pin, means on the tractor for applying the brakes hydraulically through the shifting movement of said pin, mechanical 30 brakes on the semitrailer, and means for estab- 35 lishing an operable connection between the me- chanical brake-applying means and the hydraulic brake-applying means, whereby shift of the pin in the king pin operates both the hydraulic means and the mechanical means.

6. In a tractor semitrailer combination, brakes for the wheels of the semitrailer, hydraulic means on the semitrailer for applying the brakes, a draft 40 coupling including a king pin, an axially shift- 45 able pin in the king pin, means on the tractor for applying the brakes hydraulically through the shifting movement of said pin, mechanical brakes on the semitrailer, means for establishing an operable connection between the mechanical brake- 50 applying means and the hydraulic brake-applying means, whereby shift of the pin in the king pin operates both the hydraulic means and the mechanical means, and means in the mechanical 55 brake-applying means for holding the brakes applied upon tractor semitrailer separation.

7. In a tractor semitrailer combination, a king pin on the tractor having an axially shiftable pin therein, a draft coupling means on the trailer for receiving the king pin, brakes for the wheels 60 of the semitrailer, hydraulic brake-applying means on the semitrailer including an element associated with said pin, means on the tractor for shifting the pin to apply the brakes through the hydraulic means, mechanical brake-applying 65 means on the semitrailer disassociated with the hydraulic brake-applying means, means operable to establish an operable connection between the mechanical brake-applying means and said element, whereby movement of said pin actuates 70 both the hydraulic means and mechanical means, and means in the mechanical means for holding the brakes applied.

8. In a tractor semitrailer combination, a king pin on the tractor having an axially shiftable pin 75 therein, a draft coupling means on the trailer for receiving the king pin, brakes for the wheels of the semitrailer, hydraulic brake-applying means on the semitrailer including an element associated with said pin, means on the tractor for shifting the pin to apply the brakes through the hydraulic means, mechanical brake-applying means on the semitrailer disassociated with the hydraulic 80 brake-applying means, means on the tractor operable to establish an operable connection between the 85

the mechanical brake-applying means and said element, whereby movement of said pin actuates both the hydraulic means and mechanical means, and means in the mechanical means for holding the brakes applied.

5. In a tractor semitrailer combination, a king pin on the tractor having an axially shiftable pin therein, a draft coupling means on the trailer for receiving the king pin, brakes for the wheels of the semitrailer, hydraulic brake-applying means on the semitrailer including an element associated with said pin, means on the tractor for shifting the pin to apply the brakes through the hydraulic means, means operable to condition the coupling means for tractor semitrailer separation, mechanical brake-applying means on the semitrailer disassociated from the hydraulic brake-applying means, means operable to establish a connection between the mechanical brake-applying means 10 and said element of the hydraulic brake-applying means upon movement of the means operable to condition the draft coupling for tractor semitrailer separation, and means in the mechanical brake-applying means for holding the trailer brakes applied upon tractor semitrailer separation.

10. In a tractor semitrailer combination, a king pin on the tractor having an axially shiftable pin therein, a draft coupling means on the trailer for receiving the king pin, brakes for the wheels of the semitrailer, hydraulic brake-applying means on the semitrailer including an element associated with said pin, means on the tractor for shifting the pin to apply the brakes through the hydraulic means, means on the tractor operable to condition the coupling means for tractor semitrailer separation, mechanical brake-applying means on the semitrailer disassociated from the hydraulic brake-applying means, means operable to establish a connection between the mechanical brake-applying means and said element of the hydraulic brake-applying means upon movement of the means operable to condition the draft coupling for tractor semitrailer separation, and means in the mechanical brake-applying means for holding the trailer brakes applied upon tractor semitrailer separation.

11. In a tractor semitrailer combination, a king pin on the tractor having an axially shiftable pin therein, a draft coupling means on the trailer for receiving the king pin, brakes for the wheels of the semitrailer, hydraulic brake-applying means on the semitrailer including an element associated with said pin, means on the tractor for shifting the pin to apply the brakes through the hydraulic means, means on the tractor operable to condition the coupling means for tractor semitrailer separation, mechanical brake-applying means on the semitrailer disassociated from the hydraulic brake-applying means, means operable to establish a connection between the mechanical brake-applying means and said element of the hydraulic brake-applying means upon movement of the means operable to condition the draft coupling for tractor semitrailer separation, means in the mechanical brake-applying means for holding the trailer brakes applied upon tractor semitrailer separation, means on the trailer for releasing the brakes from being held applied by the mechanical means, and means on the trailer for reapplying the brakes on the semitrailer.

12. In a tractor semitrailer combination, a king pin on the tractor having two axially shiftable service pins therein, draft coupling means on the semitrailer for receiving the king pin, brakes for

the semitrailer, hydraulic brake-applying means on the semitrailer having an element associated with one of the service pins, means on the tractor operable to shift said one service pin for applying the trailer brakes hydraulically, means on the tractor shiftable to establish a connection between the other service pin and said means on the tractor for shifting said other pin, mechanical brake-applying means on the semitrailer independent of the hydraulic brake-applying means, means operable upon shift of said other pin for establishing a connection between the hydraulic means and mechanical means whereby shift of the first mentioned service pin actuates both the hydraulic and mechanical means, and means in the mechanical brake-applying means for holding the brakes applied as the forces for shifting the first service pin are relieved.

13. In a tractor semitrailer combination, a draft coupling including a king pin on the tractor, coupling means on the semitrailer, an axially shiftable service pin in the king pin, brakes for the semitrailer, transit brake-operating means comprising hydraulic means operable upon shift of the service pin, means on the tractor for shifting the service pin, mechanical brake-applying means on the semitrailer disassociated from said service pin, a second axially shiftable service pin in the king pin, means operable at will to associate said second pin with the said means on the tractor for axial shift thereof, means on the semitrailer operable upon shift of the second service pin to condition the coupling for tractor semitrailer separation and for establishing an operable connection between the mechanical brake-applying means and the first mentioned service pin, whereby shift of the first mentioned service pin actuates the hydraulic and mechanical brake-applying means, and means in the mechanical brake-applying means for holding the brakes applied upon tractor semitrailer separation.

14. In a tractor semitrailer combination, a draft coupling including a king pin on the tractor, coupling means on the semitrailer, an axially shiftable service pin in the king pin, brakes for the semitrailer, transit brake-operating means comprising hydraulic means operable upon shift of the service pin, means on the tractor for shifting the service pin, mechanical brake applying means on the semitrailer disassociated from said service pin, a second axially shiftable service pin in the king pin, means operable at will to associate said second pin with the said means on the tractor for axial shift thereof, means on the semitrailer operable upon shift of the second service pin to condition the coupling for tractor semitrailer separation and for establishing an operable connection between the mechanical brake-applying means and the first mentioned service pin, means for maintaining the coupling conditioned for tractor semi-trailer separation and for maintaining the operable relationship between the mechanical brake-applying means and the first mentioned pin when the forces delivered to the second service pin are relieved, whereby axial shift of the first mentioned service pin actuates both the hydraulic and mechanical brake-applying means, means in the mechanical brake-applying means for holding the brakes applied upon tractor semi-trailer separation, said means which maintains the coupling conditioned for tractor semi-trailer separation and which maintains the operable relationship between the first mentioned service pin and the mechanical brakes being automatically rendered ineffective.

upon recoupling of the king pin with the coupling means on the semitrailer.

15. In a tractor semitrailer combination, a draft coupling including a king pin on the tractor, coupling means on the semitrailer, an axially shiftable service pin in the king pin, brakes for the semitrailer, transit brake-operating means comprising hydraulic means operable upon shift of the service pin, means on the tractor for shifting the service pin, mechanical brake-applying means on the semitrailer disassociated from said service pin, a second axially shiftable service pin in the king pin, means operable at will to associate said second pin with the said means on the tractor for axial shift thereof, means on the semitrailer operable upon shift of the second service pin to condition the coupling for tractor semitrailer separation and for establishing an operable connection between the mechanical brake-applying means and the first mentioned service pin, supports for the trailer moving to its supporting condition upon tractor semitrailer separation and shiftable to folded position upon tractor semitrailer connection, means operable upon movement of the supports to folded position for actuating the brake-holding means to release the brakes.

16. In a tractor semitrailer combination, brakes for the semitrailer, hydraulic brake-applying means on the semitrailer, a draft coupling including coupling means on the semitrailer and a king pin on the tractor, a service pin axially shiftable in the king pin and associated with the hydraulic brake-applying means, mechanical brakes on the semitrailer disassociated from the service pin, means on the tractor including a clutching device for shifting the service pin to apply the trailer brakes hydraulically, a second axially shiftable service pin in the king pin, means for conditioning the clutch so that actuation of the said means on the tractor shifts the second service pin, means operable by shift of the second service pin to establish an operable relationship between the mechanical brake-applying means and the first mentioned service pin, whereby shift of the first mentioned service pin actuates the mechanical brake-applying means, and means in the mechanical brake-applying means for holding the semitrailer brakes applied during tractor semitrailer separation.

17. In a tractor semitrailer combination, brakes for the semitrailer, hydraulic brake-applying means on the semitrailer, a draft coupling including coupling means on the semitrailer and a king pin on the tractor, a service pin axially shiftable in the king pin and associated with the hydraulic brake-applying means, mechanical brakes on the semitrailer disassociated from the service pin, means on the tractor including a clutching device for shifting the service pin to apply the trailer brakes hydraulically, a second axially shiftable service pin in the king pin, means for conditioning the clutch so that actuation of the

said means on the tractor shifts the second service pin, means operable by shift of the second service pin to establish an operable relationship between the mechanical brake-applying means and the first mentioned service pin and for conditioning the draft coupling for tractor semitrailer separation, whereby shift of the first mentioned service pin actuates the mechanical brake-applying means, and means in the mechanical brake-applying means for holding the semitrailer brakes applied during tractor semitrailer separation.

18. In a tractor semitrailer combination, a king pin on the tractor having first and second axially shiftable service pins therein, coupling means on the trailer for engaging the king pin, brakes for the semitrailer, means on the tractor for shifting the first service pin, hydraulic brake-applying means on the trailer operably associated with the first service pin and including a rocker shaft, mechanical brake-applying means on the semitrailer including a rocker shaft, means on the tractor for shifting the second service pin, means operable upon shift of the second service pin to operatively connect the second mentioned rocker shaft with the first service pin, whereby upon shift of the first service pin the mechanical brake-applying means is actuated to apply the brakes, and means in the mechanical brake-applying means for holding the brakes applied during tractor semitrailer separation.

19. In a tractor semitrailer combination, a king pin on the tractor having first and second axially shiftable service pins therein, coupling means on the trailer for engaging the king pin, brakes for the semitrailer, means on the tractor for shifting the first service pin, hydraulic brake-applying means on the trailer operably associated with the first service pin and including a rocker shaft, mechanical brake-applying means on the semitrailer including a rocker shaft, means on the tractor for shifting the second service pin, means operable upon shift of the second service pin to operatively connect the second mentioned rocker shaft with the first service pin and to condition the draft coupling for tractor semitrailer separation, whereby upon shift of the first service pin the mechanical brake-applying means is actuated to apply the brakes, and means in the mechanical brake-applying means for holding the brakes applied during tractor semitrailer separation.

20. In a tractor semitrailer combination, brakes for the wheels of the semitrailer, one brake-applying means on the semitrailer, other brake-applying means on the semitrailer, a draft coupling between the tractor and semitrailer, including a king pin, two axially shiftable pins in the king pin for operating the said one and said other brake-applying means, and means on the tractor for selectively shifting said pins.
